KEYHOLDER

Norman A. Dysart, Amarillo, Tex.

Application May 16, 1950, Serial No. 162,189

8 Claims. (Cl. 70—456)

This invention relates to keyholders, and more particularly keyholders of the pocket type, in which a plurality of keys are supported in such a manner, as to render them easily identifiable, and accessible, and in which the keys may be readily placed in position for use, by the operator.

While keyholders of a large variety of types are available, they are generally difficult to handle, bulky, and complicated to manipulate, particularly where only one hand is available.

The primary object of my invention is to produce a simple, compact keyholder, in which individual keys can be readily identified, and selected when required.

A further object is to produce a keyholder, in which the keys are latched in place, in such a manner that they can be readily, individually released, and placed in position for ready insertion by the operator.

A further object is to produce a keyholder, in which the outer plates are made of a transparent plastic material, so that the individual keys are readily identifiable, provision being made for indentations or, markings on the plates, so that the individual keys can be similarly identified by the sense of touch, in the dark.

Another object is to provide simple, compact latch, or retainer, for each individual key, the latch being adapted to rapidly release the corresponding key, when selected by the operator, while the other keys remain in the holder.

A primary object is to produce a simple, compact keyholder, which will retain a number of keys in a relatively small space; the keyholder being produced at relatively low cost, using simple parts, which can be produced without elaborate tools, the unit being of simple construction, so that it can be readily manipulated by persons without special skills, and which will function over sustained periods, without special attention, or complicated adjustments.

The accompanying drawings, illustrative of one embodiment of my invention, together with the description of its construction and the method of utilization and operation thereof, will serve to clarify further objects and advantages of my invention.

In the drawings:

Fig. 1 represents a plan view of the assembled keyholder.

Fig. 2 is a side elevation of the keyholder of Fig. 1.

Fig. 3 is a cross-section through the plates and the key-retaining latch, taken at 3—3, Fig. 1.

Fig. 4 is a cross-section through the plates and the separator, taken at 4—4, Fig. 1.

Fig. 5 is a plan view of one embodiment of the outer plate, of the keyholder of Figure 1, showing some of the key indentations, or markings.

Fig. 6 is a plan view of a plate, similar to Fig. 5, showing another set of key identification markings.

Fig. 7 is a section through the plates and the screw connecting them, taken at 7—7, Fig. 2.

It will be understood that the following description of the construction and operation of the keyholder, is intended as explanatory of the invention, and not restrictive thereof.

In the drawings, the same reference numerals designate the same parts throughout the various views.

One embodiment of the keyholder, shown in Figs. 1, and 2, comprises a central plate 10, made of metal, or a plastic material, of substantially oval contour, to which may be spacedly attached two or more outer side plates 11 and 12, made of "Lucite," or other suitable transparent, or translucent plastic material. The side plates may be removably attached to the central plate by a pair of screws

2

14 and 15, or other suitable attaching means, mounted near the ends of the plates, the screws being inserted either through the side plates and threadably inserted in the central plate, or each screw may be fitted through an opening formed in one side plate and the central plate, and threadably inserted in the opposite side plate.

The screws 14 and 15 serve to connect the plates, and also act as pivot mountings for the keys 16 and 17, inserted in the gap between the plates on each side, each screw fitting through an opening formed in the head of the corresponding key. A shaped spacer 18, made of a plastic material, formed metal, or other suitable material, may be attached to each face of the central plate, by means of a plurality of rivets 20, or by gluing, soldering, or other suitable attaching means, the spacers forming the gap between the side plates and the central plate, in such a manner as to clear the faces of the keys. The spacers also divide the gap between the plates into two separate compartments, as indicated in Fig. 1, each spacer limiting the angular movement of each of the keys, about the corresponding pivot screw, when the key is located in the inner position, shown in the upper section, Fig. 1.

A formed torsion spring 21, or other suitable form of spring, made of fine wire, or other suitable material, may be inserted in the gap between each set of plates, adjacent the key pivot point, one end 22, of the spring, being attached to the central plate by means of a clip 23, attached to, or formed integral with the plate, with the opposite or free end, of substantially circular contour, fitting around the head of the corresponding key, the opposite extremity 25, of each spring, engaging the side of the shank of the key, thus pressing the key outward to the position, shown by the lower key 17, Fig. 1, when the gripping mechanism is released. A fulcrum connection or clip 26, may be attached to or formed integral with the central plate, near the clip 23, to locate the arcuate section of the spring, with relation to the key, and to concentrate the spring pressure against the shank of the key.

40 A formed sheet metal latch 28, may be inserted into a depression, formed in each outer plate, adjacent the corresponding key, the rear edge 29, of the body of the latch, fitting into a slot formed in the wall of the plate, adjacent the depression, or abutting the wall of the plate at that point. The latch may be angularly mounted, with relation to the plate axis, the axis of the latch being substantially perpendicular to the axis of the shank of the key in the inner position.

45 A narrow tongue 30 may be formed integral with the body of each latch, an outer bent tip or retainer integral with the outer end of each of said tongues forming an acute angle with the tongue proper, to form a grip or retainer 31, which engages the side or edge of the shank of the key, to retain the key in the inner position, shown in the upper portion of Fig. 1, when the latch is in the normal position, the key retainer and teeth being shown in the section, Fig. 3. The tongue may be fitted through an opening formed in the plate, of a width slightly greater than the width of the tongue, to provide free movement of the tongue, and the gripping end thereof. A plurality of V-slots may be cut through the tip of the retainer, to form a series of relatively sharp, pointed teeth 32 at the end of the retainer, or a series of serrations, or other form of gripping elements may be formed at the free end of the retainer, the pointed teeth engaging the surface of the shank of the key, or the outer edge of the shank, to retain the key in the inner position, against the pressure of the torsion spring.

50 A latch may be made of thin sheet steel, or aluminum or other suitable material, of spring temper, to provide the necessary flexibility.

The body 33, of the latch, may be made of arcuate cross-section, as indicated in Fig. 3, so that when the upper surface of the body is pressed downward, the tongue 30 is raised about the junction point between the body and the tongue, the gripping end being raised out of engagement with the shank of the key, to the position shown by dot-dash lines, Fig. 3, thus releasing the shank of the key and allowing it to assume the free position, shown at the bottom of Fig. 1.

55 A ledge 34 may be attached to, or formed integral with

the upper surface of the plate, adjacent the rear edge of the body of the latch, to retain the latch body within the depression, a pair of similarly formed ledges 35 being located at the forward edge of the latch body, to retain the forward end of the latch body.

In inserting a key 16 into the holder, one of the screws 14 or 15, may be removed, the key being inserted into a gap between the plates. The screw is then inserted into the opening in the head of the key, and threadably inserted in the opposite plate, or the central plate, depending upon the type of screw used. The key may then be rotated about the pivot screw, until the grip of the latch, engages the side, or edge, of the key shank, thus retaining the key in the inner position, shown at the top of Fig. 1.

When the body of the latch is pressed inward, the gripping end of the tongue is released, thus allowing the torsion spring to rotate the key into the position, shown at the bottom of Fig. 1, in position for ready insertion into a keyhole.

The individual keys may be readily selected and identified through the transparent outer side plates 11 and 12.

In order to identify individual keys in the dark, or under conditions, in which they are not readily visible when mounted in the keyholder, a series of identifying indentations or serrations 36 and 37, may be formed in the outer surface of each of the outer plates, adjacent the ends thereof.

The indentations may take the form of a series of concentric circular lines 36, as indicated in Fig. 5, or a series of diagonal grooves may be formed in the plate, thus forming the diagonal serrations 37, shown in Fig. 5.

The indentations or serrations may also take the form of a series of ridges 38, formed perpendicular to the axis of the plate, or another series of ridges 39, formed substantially parallel to the plate axis, as indicated in Fig. 6, or the indentations or serrations may be located in various angular positions with relation to the plate axis, depending upon the number of keys supported in a particular holder, manufacturing facility, and the desired appearance.

The size and outer contour of the plates may be varied to suit a wide variety of types and sizes of keys.

The spacing of the outer plates, with relation to the central plate, may be varied to accommodate keys of various thicknesses and forms.

The plate attaching screws may be inserted through one outer plate, and threadably fitted to the opposite plate, or they may be inserted through each outer plate and threadably attached to the central plate.

The spacer between the plates may be made of a plastic material, and attached to the central plate by a plurality of rivets, or other suitable attaching means, or they may be made of metal, which is welded, soldered, brazed, or otherwise attached to the central plate.

The spacers may also be attached to the outer plate by riveting, heat sealing, or other suitable attaching means, or they may be molded integrally with each of the outer plates.

The form, contour and angular position of the latch may be varied considerably, depending upon the size and location of the keys to be accommodated in a particular holder.

It will be apparent to those skilled in the art that my present invention is not limited to the specific details described above and shown in the drawings, and that various further modifications are possible in carrying out the features of the invention without departing from the spirit and scope of the appended claims.

What I claim is:

1. A keyholder comprising a central plate, a pair of transparent outer plates mounted on opposite sides of said central plate, means separating the outer plates from the central plate to form gaps therebetween, a pair of screws removably attaching the outer plates to the central plate, each of said screws being adapted to pivotally support the head of a key, fitted between each pair of plates, a plurality of latches made of a spring material mounted on each outer plate, each of said latches comprising a body, a tongue integral with said body, and a key-gripping element at one end of said tongue, said tongue and gripping element extending through a slot in the plate on which the latch is mounted, the body of said latch being arcuate in cross-section, said latch body releasing the tongue and gripping element from the key shank, when the latch body is manually pressed inward, and a

coiled torsion spring adapted to press the shank of each key out of the keyholder when the corresponding latch is released.

2. A keyholder comprising a central plate, a pair of outer plates mounted on opposite sides of said central plate, means separating the outer plates from the central plate to form gaps therebetween, a pair of cylindrical elements threadably fitted to one of said outer plates, removably connecting the plates, each of said cylindrical elements being adapted to pivotally support the head of a key fitted between each pair of plates, a plurality of latches made of a spring material mounted on each outer plate, each of said latches comprising a body, a tongue integral with said body, and a key-gripping element at one end of said tongue, said tongue and key-gripping element extending through a slot in the plate, on which the latch is mounted, the body of said latch being arcuate in cross-section, said latch body releasing the tongue and gripping element from the adjacent key shank, when the latch body is manually pressed inward, and spring means pivotally moving the shank of each key out of the holder, when said gripping element is released.

3. A keyholder comprising a central plate, a pair of outer plates, made of a transparent material mounted on opposite sides of said central plate, a separator attached to each side of said central plate, to spacedly locate the outer plates, a pair of screws threadably fitted to one of said outer plates, removably connecting the plates, each of said screws being adapted to pivotally support the head of a key rotatably fitted between each pair of plates, a plurality of latches made of a spring material, mounted on each outer plate, each of said latches comprising a body, a tongue integral with said body, and a key-gripping element at one end of said tongue, said tongue and gripping element extending through a slot in the plate on which the latch is mounted, the body of said latch being adapted to release the tongue and the key-gripping element from the shank of the key, when the latch body is manually pressed inward.

4. A keyholder comprising a central plate, a pair of outer plates, made of transparent material, mounted on opposite sides of said central plate, a separator attached to each side of said central plate to spacedly locate the outer plates, a pair of screws removably attaching the outer plates to the central plate, each of said screws being adapted to pivotally support the head of a key between each pair of plates, each of said outer plates having a plurality of depressions therein, a latch mounted adjacent each of said outer plate depressions, each of said latches comprising a body which is arcuate in cross-section, a tongue integral with said body, and an integral key-gripping element located at the outer end of said tongue, the tongue and key-gripping element extending through a slot in the plate on which the latch is mounted, the latch body being operative to manually release the tongue and the key-gripping element from the key shank when the latch body is pressed inward, and a coiled torsion spring adapted to press the shank of the adjacent key out of the key holder, when the tongue and the key-gripping element are released.

5. A keyholder comprising a central plate, a pair of outer plates mounted on opposite sides of said central plate, means separating the outer plates from the central plate to form gaps therebetween, a pair of screws removably attaching the outer plates to the central plate, each of said screws being adapted to fit through an opening in the head of a key to pivotally support the head of a key located between each pair of plates, each of said outer plates having a plurality of depressions in the outer surface thereof, a latch mounted in alignment with each depression in each outer plate, each of said latches comprising a body fitted adjacent the depression in the plate on which the latch is mounted, a tongue integral with said body, and a key-gripping element at the outer end of said tongue, said key-gripping element having a plurality of teeth formed therein, said tongue and gripping element extending through a slot in the plate on which the latch is mounted, the body of said latch being arcuate in cross-section, each of said latches being angularly located relative to the longitudinal holder axis, the longitudinal axis of each latch being substantially perpendicular to the shank of the adjacent key, when the key is mounted within the key holder, said latch body

being adapted to release the tongue and the key-gripping element from the adjacent key shank, when the latch body is manually pressed inward, a torsion spring mounted adjacent each of said screws, between each pair of plates, means attaching one end of said spring to the central plate, the opposite end of said spring being adapted to engage the adjacent key, to angularly move the shank of the key out of the key holder, when the key-gripping element of the latch is released.

6. A keyholder comprising a central plate, a pair of outer plates, of oval contour, made of a transparent plastic material, mounted on opposite sides of said central plate, a separator attached to each side of said central plate, to spacedly locate the outer plates, a pair of screws threadably fitted to one of said outer plates, removably connecting the plates, each of said screws being adapted to pivotally support the head of a key located between each pair of plates, a plurality of latches, made of a spring material, mounted on each outer plate, each of said latches comprising a body, a tongue integral with said body, and a key-gripping element at the outer end of said tongue, said tongue and key-gripping element extending through a slot in the plate on which the latch is mounted, the body of each of said latches being arcuate in cross-section, each of said latches being angularly located relative to the longitudinal key holder axis, the longitudinal axis of each of said latches being substantially perpendicular to the shank of the adjacent key fitted to the keyholder, said latch body being adapted to release the tongue and the key-gripping element from the corresponding key shank, when the latch body is manually pressed inward, a torsion spring mounted adjacent each screw, between each pair of plates, means attaching one end of said spring to the central plate, the opposite end of said spring being adapted to engage the adjacent key, to pivotally move the shank of the key out of the key holder, when the gripping element of the latch is released.

7. A keyholder comprising a central plate, a pair of outer plates mounted on opposite sides of said central plate, a separator attached to each side of the central plate, to spacedly locate the outer plates relative to the central plate, said separators being adapted to limit the movement of keys fitted between the plates, a pair of cylindrical elements fitted to one of said outer plates, removably connecting the plates, each of said cylindrical elements being adapted to pivotally support the head of a key located between each pair of plates, each of said outer plates having a plurality of depressions in the outer surface thereof, a plurality of latches, made of a spring material, mounted on each outer plate, each of said latches comprising a body, located in alignment with the adjacent depression in the plate on which the latch is mounted, a tongue integral with said body, and a key-gripping element at the outer end of said tongue, said tongue and key gripping element extending through a slot in the plate on which the latch is mounted, the body of each of said latches being arcuate in cross-section, the longitudinal axis of each of said latches being

substantially perpendicular to the shank of the adjacent key, said latch being adapted to release the tongue and the key-gripping element from the adjacent key shank, when the latch body is manually pressed toward the plate on which the latch is mounted, and a torsion spring mounted adjacent each cylindrical element, between each pair of plates, means attaching one end of said spring to the central plate, the opposite end of each of said springs being adapted to engage the adjacent key to rotatably move the shank of the key out of the keyholder, when the gripping element of the latch is released.

8. A keyholder comprising a central plate, a pair of outer plates, made of a transparent plastic material, mounted on opposite sides of said central plate, a separator attached to each side of said central plate, to spacedly locate the outer plates relative to the central plate, a pair of screws, threadably fitted to one of said outer plates, removably connecting the plates, each of said screws being adapted to pivotally support the head of a key located between each pair of plates, each of said outer plates having a plurality of depressions in the outer surface thereof, a plurality of latches, made of a spring material, mounted on each outer plate, each of said latches comprising a body, fitted to the adjacent depression in the plate on which the latch is mounted, a tongue integral with said body, and a key-gripping element extending through a slot in the plate on which the latch is mounted, the body of each of said latches being arcuate in cross-section, the longitudinal axis of each of said latches being angularly located relative to the longitudinal keyholder axis, the longitudinal latch axis being substantially perpendicular to the shank of the adjacent key, when the key is mounted within the key holder, said latch body being adapted to release the tongue and the key-gripping element from the adjacent key shank when the latch body is manually pressed inward toward the plate on which the latch is mounted, a torsion spring mounted adjacent each screw, between each pair of plates, means attaching one end of said spring to the central plate, the opposite end of said spring being adapted to engage the adjacent key to angularly move the shank of the key out of the keyholder, when the gripping element of the latch is released.
